Fig. 2

Fig. 3

FIG. 5

FIGURE 1 is a perspective view of a therapeutic lamp showing my new design, with the standard shown broken away in part to indicate indeterminate length.

FIGURE 2 is a top plan view of the lamp.

FIGURE 3 is a side view of the lamp, it being understood that the opposite side view is identical.

FIGURE 4 is a rear view of the lamp.

FIGURE 5 is a front view of the lamp.

The base and standard members are omitted in FIGURES 2, 3, 4 and 5 for convenience of illustration. The dominant features of my design reside in the portions shown in full lines.

I claim:

The ornamental design for a therapeutic lamp, substantially as shown and described.
